UNITED STATES PATENT OFFICE.

JULIUS LEVY, OF SAN FRANCISCO, CALIFORNIA.

REFLECTOR FOR LAMPS.

SPECIFICATION forming part of Letters Patent No. 359,794, dated March 22, 1887.

Application filed August 3, 1885. Serial No. 173,449. (No model.)

To all whom it may concern:

Be it known that I, JULIUS LEVY, a citizen of the United States, residing at San Francisco, in the county of San Francisco and State 5 of California, have invented a new and useful Reflector for Lamps, &c., of which the following is a specification.

My invention relates to improvements in reflector lamp-shades, in which a reflector and shade is combined in one and the same article of manufacture; and it consists in the construction and combination of parts, substantially as will be hereinafter described, and then pointed out in the claim.

15 In the accompanying drawings, forming a part of this specification, Figure 1 is a view in elevation of a lamp-shade embodying my invention. Fig. 2 is a vertical section of the same. Figs. 3 and 4 are views in detail or 20 sections of neck or rim and lower edge of the body of the shade and reflector.

In carrying out my invention I construct my shade and reflector for lamps and other light-imparting devices hollow from the lower 25 edge, A, to the upper edge or top of the neck B, and both the upper and lower edges of the reflector are made rounding. At suitable intervals of space around both the upper edge of the neck and lower edge of the body of my 30 reflector I make small apertures C, which lead into and out of the hollow space formed within. The object of this construction is threefold: first, to provide a means for the introduction of the silvering material to silver the interior 35 of the reflector, which silvering material is introduced through one or more of the holes or apertures, and the shade shaken or revolved until the whole interior is lined or coated with the reflecting-substance and becomes a double 40 reflector—that is to say, a reflector having reflecting-surfaces within and without; secondly, by this construction of the shade and reflector

a current of cold air is constantly being drawn up into the hollow space or body of the reflector through the lower apertures and passes 45 out through the upper apertures, so that the silvering substance will not be dispelled or dissipated; thirdly, when expansion and contraction of the parts takes place by heating and cooling, fracture will be prevented by the 50 deflected heat from the burner or burners.

I have illustrated only one shape or size of my reflector in form of a lamp-shade; but it is evident that it can be constructed of different sizes and various shapes, so long as it is 55 made with double continuous walls, with apertures opening into the chamber or hollow space between the walls from the upper and lower edges thereof. When made in the form shown, strengthening rings D are formed 60 around the neck, and the whole shade and reflector is supported by the usual bent-wire holder, made and applied so as not to interfere with the apertures.

Having thus described my invention, what 65 I claim, and desire to secure by Letters Patent, is—

A reflector or shade for lamps, having its body and neck portions constructed with double walls which are coated with a silvering material, and provided, also, with a series 70 of apertures near the top of the reflector, and another series of apertures near its bottom which lead into the chamber between the said double walls, and thus allow a current of cold 75 air to pass through it, substantially as shown and described.

In testimony that I claim the foregoing I have hereunto set my hand and seal.

JULIUS LEVY. [L. s.]
